CLAIM

The ornamental design for a finger spinner, as shown and described.

DESCRIPTION

FIG. 1 is a perspective view of the finger spinner showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view of the finger spinner, illustrating the finger spinner associated with the finger of a user.

The broken line representation of the human finger is for illustrative purposes only and forms no part of the claimed design.
